(57) **CLAIM**

The ornamental design for a large foldable snap box, as shown and described.

DESCRIPTION

FIG. 1 is a front isometric view of a large foldable snap box showing the claimed design, with a closed lid;

FIG. 2 is a rear isometric view of the large foldable snap box in FIG. 1;

FIG. 3 is a bottom perspective view of the large foldable snap box in FIG. 1;

FIG. 4 is a front perspective view of the large foldable snap box in FIG. 1;

FIG. 5 is a front view of the large foldable snap box in FIG. 1;

FIG. 6 is a left side view of the large foldable snap box in FIG. 1;

FIG. 7 is a right side view of the large foldable snap box in FIG. 1;

FIG. 8 is a front isometric view of a large foldable snap box with an open lid;

FIG. 9 is a right side rear isometric view of the large foldable snap box in FIG. 8;

FIG. 10 is a right side bottom perspective view of the large foldable snap box in FIG. 8;

FIG. 11 is a left side rear isometric view of the large foldable snap box in FIG. 8;

FIG. 12 is a left side bottom perspective view of the large foldable snap box in FIG. 8;

FIG. 13 is a top perspective view of the large foldable snap box in FIG. 8;

FIG. 14 is a left side perspective view of the large foldable snap box in FIG. 8;

FIG. 15 is a right side perspective view of the large foldable snap box in FIG. 8;

FIG. 16 is a top view of the large foldable snap box in FIG. 8;

FIG. 17 is a front perspective view of the large foldable snap box in FIG. 8;

(Continued)

FIG. 18 is a back side rear isometric view of a large foldable snap box in an unfolded configuration and showing what becomes the interior portions of the box when folded; FIG. 19 is a front side isometric view of the large foldable snap box of FIG. 18 showing what becomes the exterior portions of the box when folded; FIG. 20 is a front side perspective view of the large foldable snap box of FIG. 18; FIG. 21 is a top view of the large foldable snap box of FIG. 18; and, FIG. 22 is a bottom view of the large foldable snap box of FIG. 19. The broken lines in the figures depict environmental subject matter and form no part of the claimed design.
